Arthur F. Pitkin,
by *Arthur F. Pitkin*

UNITED STATES PATENT OFFICE.

ARTHUR F. PITKIN, OF SCHENECTADY, NEW YORK.

METHOD OF APPLYING STAY BOLTS.

Original application filed May 24, 1926, Serial No. 111,172. Divided and this application filed January 29, 1927. Serial No. 164,634.

My invention relates to methods of applying stay bolts to the shell and firebox sheets of boilers, and has, for an object, to provide a method which can be rapidly and inexpensively performed, and which will produce a steam tight jointure of great durability and strength.

This application is a division of my co-pending application, filed May 24, 1926, Ser. No. 111,172.

In the practice of my invention, I form that section of the bolt which is attached to the firebox sheet, with a central tell-tale bore, and an external screw thread. The threaded end 15 of the section is first screwed into a correspondingly threaded opening, formed in the firebox inner sheet. A tapered recess is then reamed in the end of the bolt to facilitate expanding the bolt into steam tight fit with the 20 wall of the opening in the fire box sheet. The tapered recess is limited in length, so that it will terminate intermediate the inner and outer faces of the fire box sheet. This form 25 of construction is adopted for the purpose of ensuring a sufficient body of metal, contiguous to the outer surface of the sheet, to efficiently withstand the sheering stresses, incident to service. The next step of the method is that of inserting an expanding tool into 30 the tapered recess, and expanding the recessed portion of the bolt into steam tight fit with the wall of the opening. A heading operation is next performed, whereby the end 35 of the bolt is upset to provide an annular head or flange that overlies the inner face of the firebox sheet.

The improvement claimed is hereinafter fully set forth.

In the accompanying drawing: Figure 1 is 40 a view, partly in vertical section, through a staybolt, and the shell and firebox sheets to which it is attached, the inner end of the bolt being shown with the tapered recess reamed therein, the recessed end being unexpanded; Fig. 2, a side view, in elevation, of the reamer employed to form the tapered recess; Fig. 3, a view, partly in vertical section, of the lower portion of the bolt and the firebox sheet, showing the recessed end after it has been 45 expanded; Fig. 4, a side view, in elevation, of the expanding tool; Fig. 5, a view, similar to Fig. 3, showing the recessed end after it has been headed; Fig. 6, a side view, in elevation, of the heading tool; Fig. 7, a view, similar to Fig. 3, showing a tapered opening in the 50 firebox sheet, the recess end of the bolt being unexpanded.

In the practice of my invention, referring descriptively to the specific embodiment thereof which is herein exemplified, I employ 60 a staybolt structure of the articulated type, comprising a main section, 5, having a socket, 6, formed at its upper end, and a socket, 7, formed at its lower end. The upper socket, 6, is jointed to a ball-shaped head, formed on the lower end of the upper section, 9, which is anchored to the shell sheet. The section, 9, has, preferably, a tapered formation, and is welded, as at 11, or otherwise secured to the edges of the opening in the shell sheet, 10, 65 in which it is seated. The lower socket member, 7, of the main section, 5, of the bolt, is jointed to a ball-shaped head, 12, formed on the upper end of the lower end section, 13. The lower end section is formed with a centrally disposed tell-tale bore, 15, and with an external screw thread.

In practicing my improved method, the lower end section, 13, of the bolt, is first 70 screwed into the threaded opening in the firebox sheet. A reaming tool, 18, is then inserted in the tell-tale bore, and sufficient metal reamed away to provide the tapered recess, 16. The object of forming the recess is to facilitate the expansion of the lower 75 section into steam tight jointure with the walls of the opening in the firebox sheet. The tapered recess is made of limited length so that it will terminate intermediate the inner and outer faces of the firebox sheet. 80 This is done to ensure a sufficient thickness of metal in that portion of the lower section of the bolt, contiguous to the outer surface of the firebox sheet, to adapt the bolt to efficiently withstand the sheering stresses, 85 encountered in service. A special reaming tool, 18, is employed to form the tapered recess. This tool is provided with a stop, 19, adapted to bear on the firebox sheet when the recess has been reamed to the proper depth, and 90 thus positively prevent the recess being reamed to too great a depth.

After the recess has been reamed, the expanding tool, 20, is inserted therein, and the recessed portion of the bolt is swaged or expanded into steam tight fit with the walls 95 of the opening in the firebox sheet.

The next step in the method is that of upsetting the end, 22, of the lower section, 13, of the bolt, to form the annular flange or head, 110

23, which overlies the inner face of the firebox sheet. This operation is performed by the heading tool, 21.

A modified method of fastening the stay-bolt is illustrated in Fig. 7. This method differs from that hereinbefore described, in that the threaded opening in the firebox sheet is formed with a taper, flaring from the outer to the inner face of the firebox sheet.

I claim as my invention and desire to secure by Letters Patent:

1. The method of attaching a staybolt to a firebox sheet, which comprises screwing a threaded end of a staybolt into an opening in the firebox sheet; reaming a tapered recess in said end to a depth limited to dispose the inner end of the recess intermediate the inner and outer faces of the firebox sheet; expanding the recessed portion of the bolt into steam tight fit with the walls of the opening; and then upsetting the walls of the outer end of the recess, to provide a flange overlying the inner face of the firebox sheet.

opening in the firebox sheet; and then upsetting the walls of the outer end of the recess, to provide a flange overlying the inner face of the firebox sheet.

2. The method of attaching a staybolt to a firebox sheet, which comprises forming a tapered staybolt opening in the sheet, the opening flaring from the outer to the inner face of the sheet; screwing a threaded end of a staybolt into said opening; reaming a tapered recess in said fitted end to a depth limited to dispose the inner end of the recess intermediate the inner and outer faces of the firebox sheet; expanding the recessed portion of the bolt into steam tight fit with the walls of the opening; and then upsetting the walls of the outer end of the recess, to provide a flange overlying the inner face of the firebox sheet.

ARTHUR F. PITKIN.
